ATTORNEY.

UNITED STATES PATENT OFFICE.

ALBERT G. SMOLENSKY, OF CLEVELAND, OHIO.

SWING.

Application filed June 1, 1928. Serial No. 282,221.

This invention relates to swings, and particularly to swings designed for the use of children and which are worked by the child sitting in the seat and operating a crank handle or lever which produces swinging motion of the seat between the side frames or supports.

The object of the invention is to provide an improved device of this kind which can be cheaply produced in different forms or designs and which can be readily set up for use when desired.

A further object of the invention is to provide an exercising device of the character described by means of which the child who uses it will be benefitted in the development of its body muscles.

Another object of the invention is to improve the operating connections between the seat and the frame and the operating lever, providing convenient and easy operation by a child in the seat.

One form of the invention is shown in the accompanying drawings in which Fig. 1 is a side view of the swing showing one position in full line and another position in dotted lines. Fig. 2 is a front view of the swing. Figs. 3, 3^a and 3^b are details of one of the seat hangers. Fig. 3^c is a detail of a modified form of hanger. Fig. 4 is a detail of the handle connections. Fig. 4^a is a detail of one of the parts thereof.

Referring particularly to the drawings 1 indicates two side frames which may be designed in the shape of a horse or in any other shape as desired, and made of wood or other materials. A brace 2 may be placed between the front legs of the two frames, and a brace 3 between the rear legs, and a round brace or stick 4 between the heads. The swinging seat box 5 hangs between the two side frames, being suspended by four hangers or links. Each of these may consist of a rod 6^a having a hook 22 at its upper end engaged in a pocket 24 in a washer 7 having points which may be driven into the side frames 1 and also fastened by screws in the holes 26. The lower end of the rod has an eye 23^a engaging a hook 28 on a bracket 8^a which has teeth 27 which may be driven into the sides of the seat box 5 and also fastened by screws in the holes 26^a. Or the links may each consist of a rod 6 bent at the top to form a pivot 22^b inserted in a hole in a washer 16 and bent at the lower end to form a hook 23^b engaging under the side piece of the seat box 5 and held by a staple 8^b.

For operating the swing seat a handle 20 is provided the ends of which receive the bent ends 14 of lever rods 13, said ends being inserted through caps 21 on the ends of the handle bar. The lower ends of the rods 13 are bent as at 15 to fit through holes in washers 16^a on the inside of the side frames 1. The rods 13 extend at a sliding fit through tubular members 17 which have ears 17^a connected by pivots 18 extending through holes in said ears and through washers 19 fixed to the sides of the seat frame 5 at or near the top thereof. The crank levers 13 may thus slide in the connecting members 17 which will also turn on the pivots 18 to permit the angular movement.

The operation is evident: by pulling or pushing on the handle 20 the swinging motion of the levers is communicated to the seat to swing the same, and the handle may be conveniently operated by a child sitting in the seat, the lever 13 working in the space between the sides of the seat and the sides of the supporting frame.

The construction provides a very simple cheap and effective means for operating the swing by an occupant of the seat. The seat box may comprise a seat bottom 11, a back 10, a foot rest 12 and a front board 9 fixed between the side frames 5.

Various modifications may be made within the scope of the invention.

I claim:

1. A swing comprising two side frames, a swinging seat hung between said frames, and a crank handle extending across in front of the seat and having levers pivoted at their lower ends to the side frames and having sliding pivotal connections with the seat above said pivots, said pivotal connections comprising tubular members in which the levers are slid able, said members being pivoted to the sides of the seat.

2. A swing comprising two side frames, a swinging seat hung between the two frames, a cross handle extending across in front of the seat and having levers pivoted at their lower ends to the side frames, and sliding pivotal connections between the levers and the seat, said pivotal connections comprising washers secured to the seat and tubular members in which the levers slide and pivots extending through said members and washers.

In testimony whereof, I do affix my signature.

ALBERT G. SMOLENSKY.
